UNITED STATES PATENT OFFICE

2,324,498

HONE

George W. Emmert, Chicago, Ill.

Application June 18, 1942, Serial No. 447,487

12 Claims.

(Cl. 51—211)

This invention relates to a hone and has for an object the provision of an improved hone which is particularly suitable for simultaneously sharpening both edges of a double-edged safety razor blade.

In accordance with one embodiment of this invention, the hone comprises a flat sheet having an embossment therein extending out of the plane of the sheet and a facing of abrasive material integrated with the inside surfaces of the embossment to provide a suitable honing surface. The flat sheet is preferably prepared from heavy paper-like material which is capable of being embossed by means of a suitable die to produce the desired embossment. The flat sheet may be provided with an integral flap which is capable of being folded over the sharpening or honing surface to provide protection therefor when the hone is not in use, and the flap may also be provided with an embossment similar to that in the flat sheet to provide an enclosure when the flap is folded over the flat sheet. The enclosure so formed is adapted to serve as a receptacle for one or more safety razor blades when the hone is not in use.

The embossing in the flat sheet preferably has gradually sloping side walls which meet in a central portion of the embossment so that a razor blade may be positioned thereon and gently rotated with the exertion of slight pressure whereby a desired sharpening or honing is effected as will hereinafter be more fully described. The hone of this invention is readily prepared, is light in weight, and occupies a minimum of space when not in use.

For a more complete understanding of this invention reference will now be had to the drawings, in which:

Figure 1 is a perspective view of a hone constructed in accordance with one embodiment of this invention showing a razor blade in dotted lines positioned on the honing surface thereof;

Fig. 2 is a cross-sectional view of the hone shown in Fig. 1 showing the flap positioned over the honing surface; and

Fig. 3 is a sectional view taken along the line 3—3 of Fig. 2.

Referring now to the drawing, the hone there shown comprises a flat sheet 10 of heavy paper or paper-like material having a centrally positioned embossment 12 extending out of the plane thereof. The embossment is provided with end walls 14 and rectangularly-shaped side walls 16, which latter present substantially flat surfaces in the central portions thereof and slope

gradually to meet in a central portion of the embossment. A sheet of abrasive material 18 is adhesively secured to the inside walls 16 of the embossment as shown in the drawing. This sheet of abrasive material may comprise waterproof paper with which has been associated finely divided particles of a suitable abrasive, such as carborundum or the like. However, it will be clear that the abrasive particles may be directly integrated with the side walls of the embossment if desired.

The sheet 10 is provided with an integral flap 20 which is adapted to be folded over the sheet 10 to provide a protective covering for the honing surface on the side walls of the embossment 12. The flap 20 is also provided with an embossment 22 having end walls 24 and side walls 26, which embossment is similar to the embossment 12 positioned in the sheet 10. When the flap 20 is folded over the sheet 10, the embossments 22 and 12 are in registering relationship and provide an enclosure or receptacle in which safety razor blades may be carried when the hone is not in use. As shown in the drawing, the sheet 10 and the flap 20 may be prepared from a single sheet of paper-like material which is divided into two sections and is capable of being folded over on itself along the scored line 28. If desired the inside side walls 26 of the embossment 22 may be provided with an abrasive or honing surface (not shown) which is also adaptable simultaneously to sharpen both edges of a double-edged safety razor blade in the same manner as the abrasive surface associated with the inside side walls of the embossment 12. In such a case it may be desirable that the abrasive material secured to the embossment 22 be somewhat finer grained than that secured to the embossment 12 so that a suitable finish may be provided on the sharpened edges of the blade.

In order to sharpen a safety razor blade on the hone of this invention, a blade 30 may be positioned on the honing surface 18 of the hone so that the side edges of the blade contact the abrasive as shown in the dotted lines of the drawing. A circular motion is then imparted to the blade by the fingers with the simultaneous application of slight pressure until the desired sharpening has been effected. The hone may be used dry, or if desired a small amount of water may be applied to the honing surface in order to assist in the sharpening. If water is used, the support for the abrasive particles should be prepared from a waterproof material.

55 It will, of course, be clear that many modifica-

tions may be made in the structure described in detail in the foregoing without departing from the spirit and scope of this invention. For example, the embossment 22 may be dispensed with in the flap 20. Also, the embossment 12 may be provided with gradually sloping side walls 16 as shown most clearly in Fig. 2, or the cross-sectional configuration of the embossment may be substantially concave if desired. I have discovered, however, that somewhat more effective sharpening of the blade is obtainable if each of the side walls 16 of the embossment presents a substantially flat surface in the central portion thereof as illustrated in Fig. 2.

It will be clear from the foregoing that I have provided a new and improved hone which may be cheaply and readily prepared from sheet material which is capable of being embossed. Embossing paper capable of receiving the embossment contemplated in the hone of this present invention is well known and is readily available on the market. Such paper is relatively heavy and is sufficiently stiff so that the embossment will retain its shape even though the hone may be subjected to a reasonable amount of abuse.

While one particular embodiment of this invention is shown above, it will be understood, of course, that the invention is not to be limited thereto, since many modifications may be made and it is contemplated, therefore, by the appended claims, to cover any such modifications as fall within the true spirit and scope of this invention.

I claim:

1. A hone comprising a substantially flat sheet having an embossment therein extending out of the plane thereof, a facing of abrasive material integrated with said embossment to provide a honing surface, and a protecting covering for said facing.

2. A hone comprising a substantially flat sheet having an embossment therein extending out of the plane thereof, a facing of abrasive material integrated with the inner surface of said embossment to provide a honing surface, and a flap integral with said sheet adapted to be folded over said facing.

3. A hone comprising a flat sheet of paper-like material score to provide two sections one of which is foldable over the other, one of said sections being provided with an embossment extending out of the plane thereof, and a facing of abrasive material integrated with said embossment to provide a honing surface on that face of said one section which is adapted to be covered by the other section when folded.

4. A hone comprising a flat sheet of paper-like material scored to provide two sections one of which is foldable over the other, embossments in each of said sections extending in the same direction out of the plane of the sheet whereby an enclosure is formed by said embossments when said sections are folded together, and a facing

of abrasive material integrated with the inner surface of at least one of said embossments to provide a honing surface thereon.

5. The hone recited in claim 4 wherein said facing comprises a sheet of waterproof paper having an abrasive powder intimately associated therewith.

6. A hone for double-edged safety razor blades comprising a flat sheet of heavy paper-like material scored to provide two sections one of which is foldable over the other, centrally positioned embossments in each of said sections extending in the same direction out of the plane of the sheet whereby an enclosure is formed by said embossments when said sections are folded together, said embossments having gradually sloping, substantially rectangularly shaped side walls having substantially flat surfaces and meeting in a central portion thereof, and a facing of abrasive material integrated with the inner surfaces of the side walls of at least one of said embossments, said facing having an area greater than the area of an ordinary safety razor blade and providing a honing surface whereby both edges of a double-edged safety razor blade may be simultaneously sharpened thereon.

7. A hone comprising a substantially flat sheet having an embossment therein extending out of the plane thereof, said embossment having side walls extending parallel to a single line and having a surface area greater than the area of an ordinary safety razor blade, said side walls being provided with a sharpening surface whereby both edges of a double-edged safety razor blade may be simultaneously sharpened thereon.

8. A hone comprising a substantially flat sheet having an embossment therein extending out of the plane thereof, said embossment having side walls extending parallel to a single line for a distance greater than the length of an ordinary safety razor blade, the inner surfaces of said side walls being provided with a facing of abrasive material whereby both edges of a double-edged safety razor blade may be simultaneously sharpened thereon.

9. The hone recited in claim 8 wherein the side walls of the embossment are substantially rectangular in shape and slope gradually out of the plane of the flat sheet and meet along a line in a central portion of the embossment.

10. The hone recited in claim 8 wherein the side walls of the embossment are substantially curvilinear in cross-section to provide a substantially concave embossment.

11. The hone recited in claim 8 wherein the embossed flat sheet comprises heavy paper-like material.

12. The hone recited in claim 8 wherein said facing comprises a sheet of waterproof paper having an abrasive powder intimately associated therewith.

GEORGE W. EMMERT.
